Primary Examiner — George D Kirschbaum*Assistant Examiner* — Jennifer Watkins(74) *Attorney, Agent, or Firm* — Muncy, Geissler, Olds & Lowe, P.C.(57) **CLAIM**

The ornamental design for a dried noodle, as shown and described.

DESCRIPTION

1.-2. Dried noodles

1.1 : Perspective

1.2 : Front

1.3 : Back

1.4 : Left

1.5 : Right

1.6 : Top

1.7 : Bottom

1.8 : Enlarged perspective view of left end part

1.9 : Enlarged left view

1.10 : Enlarged right view

2.1 : Perspective

2.2 : Front

2.3 : Back

2.4 : Left

2.5 : Right

2.6 : Top

2.7 : Bottom

2.8 : Enlarged perspective view of left end part

2.9 : Enlarged left view

2.10 : Enlarged right view

Dried noodles which have grooves on the outer peripheral portions thereof; the grooves are twisted at a rate of 60 degrees rotational angle to the central axis of the noodles per 25 cm length in the axial direction; the axial length of each dried noodle is 125 times to its diameter.

1 Claim, 20 Drawing Sheets(56)
